UNITED STATES PATENT OFFICE.

ALBERT OLIVER, OF NEW YORK, N. Y.

PLASTER-GROUND.

1,385,466.

Specification of Letters Patent. Patented July 26, 1921.

Application filed June 28, 1919. Serial No. 307,399.

To all whom it may concern:

Be it known that I, ALBERT OLIVER, a citizen of the United States, and a resident of New York city, in the county and State of New York, have invented new and useful Improvements in Plaster-Ground, of which the following is a full, clear, and exact description.

Among the principal objects which the present invention has in view are: to prevent fractures in plastered or cemented surface structures; to provide a metal bond for concrete structures for dissipating lines of fracture in the cement; to reduce the necessary thickness in wall structures; to save concrete; and to insure uniform thickness to concrete wall structures.

Drawings.

20 Figure 1 is a side view of a fragment of plaster ground, constructed and arranged in accordance with the present invention.

Fig. 2 is a detail view on enlarged scale showing a section of the structure seen in 25 Fig. 1, section being taken as on the line 2-2 in said Fig. 1.

Fig. 3 is a section on the same scale showing a modified form of the invention.

Fig. 4 is a detail view showing a back 30 view of a fragment of ground, constructed in accordance with the modified form of the invention.

Fig. 5 is a detail view on enlarged scale showing the fasteners for uniting the continuous backing sheet with the reinforce sheet of the ground when it is desired to arrange the same to receive concrete surface on one side, only, of said ground.

Description.

40 Heretofore, reinforced sheathing having a suitable paper or fabric backing has been used in connection with suspension rods and an auxiliary netting or wire fabric of lighter grade. Also wire fabric has been employed as a covering for wood sheathing of suitable construction. The former method of construction has proved objectionable in that, lines of fracture have been established parallel with the reinforcing rods.

The wire fabric above referred to has been employed in an endeavor to check or dissipate these fissures or lines of fracture.

While, to some extent, they have been successful they have established another objection, in that the concrete when disposed on

the rods, has been laid in established lines or areas in which the various thicknesses on established lines have promoted fracture of the material along these lines.

60

Objection has existed to the use of the ground on the wood sheathing or siding in that, certain building structures are not readily adapted to the employment of wood sheathing, and further that, when wood is employed, a surface drying occurs which is not desirable for the concrete face.

65 The above stated objections are overcome in the present invention wherein the numeral 10 is used to designate a sheet of heavy tarred or building paper which has been rendered waterproof. Superposed on the sheet 10 is a continuous sheet of metal fabric in which the hanging rods 11 are structurally united by interwoven binding wire 12. The wire 12 is weaved upon the rods 11 to form connections therewith and projections 13 at the junction of said wire and said rods.

70 It will be understood that the meshed sheet is made in relatively narrow lengths of any desired dimension and generally in accordance with building specification so that the rods 11 are suspended from the floor beams of one story and secured to the floor beams of the lower story. In securing this 75 ground in position, the rods 11 are bent to impart thereto a tension.

75 When constructing the herein described ground, one sheet of metal fabric is disposed on an operating table. The continuous sheet 10 is then superposed upon the meshed sheet which has been laid on the table and a second meshed sheet is then superposed on the continuous sheet.

80 As seen best in Fig. 2 of the drawings, care is exercised to arrange the meshed sheets in such manner that the rods 11 are in the same plane or juxtaposed in close relation to one another with the sheet 10 intervening. In this position, metal clips, 100 staples or tie members 14 are driven through the paper sheet 10 and bound around the rods 11, the ties being twisted until the rods are drawn tightly upon the intervening paper sheet 10.

85 As seen best in Fig. 1 of the drawings, the clips 14 are preferably staggered in their relation to form triangularly related points of attachment.

90 When grounds are thus constructed, it will 110 be observed that the paper is firmly supported to resist any usual strain imposed

thereupon when laying the plaster or concrete which is spread by means of trowel or spray. On both faces of the ground when suspended in position, a substantial partition may be thus constructed which occupies a relatively small floor of space.

When a ground is to be provided having one surface thereof only prepared to receive the plaster or concrete, the method preferred is to use metal straps 15, which have upstanding members 16, preferably punched therefrom at intervals corresponding with the intervals between the rods 11. When constructing the ground for spreading the concrete on one side thereof, and when using the straps 15, the straps 15 are first laid upon the operating table at suitable intervals in parallel relation with the members 16, preferably in staggered relation. The paper sheets 10 are then overlaid upon straps 15 and pressed thereon to force the members 16 therethrough. The paper thereafter serves to steady the position of the straps 15.

The meshed sheet is then overlaid upon the paper sheet with the rods 11 extending transverse the straps 15, each of the said rods being disposed adjacent to or juxtaposed to certain of the members 16. In this position, the members 16 are then overlaid upon the adjacent rod 11 and coiled tightly down thereupon, as shown best in Fig. 3 of the drawings. This having been accomplished, it will be found the sheet 10 and the meshed sheet having the rods 11 and the connecting wire 12 are held firmly together as a unit.

A single-faced ground may now be suspended on a metal or other skeleton structure with the meshed sheet disposed outwardly so that concrete or plaster may be spread thereover entering behind and involving the rods 11 and the connecting wire 12.

It will be noted that the wire 12 and rods 11 are so interwoven that lines of fracture will be dissipated if such should occur, and the concrete or plaster is held firmly in all directions.

It will be understood that when desired, the reinforce used at opposite sides of the continuous sheet 10 may vary in weight and dimension to accommodate constructions where the plastered surfaces are relatively heavy and light, or thick and thin, such as might occur where an exposed surface thick-

ness is formed on one side of the ground, and an interior surface is formed on the other side of the ground.

Claims.

1. An article as characterized comprising, a continuous sheet of flexible fibrous material; a reinforce for said fibrous material embodying a plurality of straight suspension rods disposed in parallel spaced relation; and a binding medium, said medium consisting in a wire interwoven between said rods, said wire being wrapped on said rods. 65

2. An article as characterized comprising, a continuous sheet of flexible fibrous material, said material being rendered impervious to water; a plurality of reinforcing sheets, said sheets being disposed at opposite sides of said continuous sheet, each of said reinforcing sheets embodying a plurality of suspension rods, said rods being disposed in parallel and spaced relation, and a binding medium between said rods, said medium consisting in a flexible wire woven between said rods to form intervening meshes, said wire 70 being wrapped on each of said rods forming anchoring projections thereon; and means for structurally uniting said continuous sheet and said reinforcing sheet as a unit structure, said means embodying metal tie 75 members passing through said continuous sheet and around said suspension rods to hold said suspension rods in superposed parallel relation.

3. An article as characterized comprising, a continuous sheet of fibrous material, said material being impervious to water; a metal reinforcing sheet superposed on said continuous sheet, said reinforcing sheet embodying a series of parallel spaced suspension rods, and binding wire interwoven between said rods to form meshes disposed therebetween, said wire being wrapped around said rods to form anchoring projection thereon; and a plurality of flat metal strips being disposed against, on the side of said continuous sheet opposite that supporting said reinforcing sheet, said metal strips having a plurality of spur-like members integrally formed thereon, said spur-like members being extended through said continuous sheet and bent over to structurally engage said reinforcing sheet for increasing the rigidity of said reinforcing sheet. 100 105

ALBERT OLIVER.
